UNITED STATES PATENT OFFICE.

THADDEUS J. LORDS, OF CHICAGO, ILLINOIS, ASSIGNOR TO SEARS, ROEBUCK AND CO., OF CHICAGO, ILLINOIS, A CORPORATION OF NEW YORK.

DESIGN FOR SHEET-ROOFING.

52,538.

Specification for Design.

Patented Oct. 8, 1918.

Application filed April 8, 1918. Serial No. 227,382. Term of patent 14 years.

To all whom it may concern:

Be it known that I, THADDEUS J. LORDS, a citizen of the United States, residing at Chicago, in the county of Cook and State of Illinois, have invented a new, original, and ornamental Design for Sheet-Roofing, of which the following is a specification, reference being had to the accompanying drawing, forming a part thereof.

The figure is a plan view of a piece of sheet roofing showing my new design.

I claim:

The ornamental design for sheet roofing, as shown.

THADDEUS J. LORDS.
